UNITED STATES PATENT OFFICE.

HENRY E. MAXWELL, OF CHICAGO, ILLINOIS.

ADJUSTABLE SCHOOL SEAT AND DESK.

1,200,389.

Specification of Letters Patent.

Patented Oct. 3, 1916.

Application filed February 10, 1915. Serial No. 7,218.

To all whom it may concern:

Be it known that I, HENRY E. MAXWELL, a citizen of the United States, and a resident of the city of Chicago, in the county of Cook and State of Illinois, have invented certain new and useful Improvements in Adjustable School Seats and Desks; and I do hereby declare that the following is a full, clear, and exact description of the 5 same, reference being had to the accompanying drawings, and to the numerals of reference marked thereon, which form a part of this specification.

The variation in size of pupils in the 15 grammar school grades is considerable, and difficulty is often experienced in properly seating a large number of children on this account. A number of experimental tests made in classrooms has demonstrated that 20 the backwardness and apparent mental deficiency of certain pupils is directly traceable to the fact that the pupils are compelled to sit in an incorrect posture, either being too large or too small for the seat and 25 desk at which they are placed. Then, too, physical deformities are liable to result where the child is incorrectly seated, or even if correctly seated, is caused to work upon a desk which is at an improper height.

30 This invention relates to an adjustable desk and seat which may be easily adjusted, requiring no special tools for the purpose, and when adjusted, locked rigidly in position. Heretofore the objection to the design 35 of the adjustable school seats and desks has been the number of complicated parts involved, making manufacture thereof expensive, and introducing difficulties in adjusting the same, requiring an expert for 40 the purpose. By my invention, however, the instructor or even a child, may readily adjust the seat and desk to proper positions, and the design has been simplified with the end in view of providing a device capable 45 of being manufactured at low cost. This is largely due to an improved hinge construction which requires no machining, and which forms a part of the adjustable mechanisms of the device. It is an object, therefore, 50 of this invention to construct an adjustable school seat which, by the detachment of a single locking element, permits adjustment of the seat, raising or lowering the same as desired, and when adjusted, attachment of said element serving to hold 55 the seat rigidly locked in position.

It is also an object of this invention to construct an adjustable school seat embracing a hinge of novel construction with the parts inseparably connected with one another and when attached to the seat, permitting folding of the same into position out of use, and furthermore, adjustable on the frame to permit raising and lowering of the seat, as desired. 60

It is also an important object of this invention to construct a device embracing a frame provided with notched slots adapted to receive the gudgeon pins of frame elements to support a desk and seat therein, 70 permitting adjustment of each thereof independently of the other in the frame, and with mechanisms readily attachable and detachable from said gudgeon pins, to rigidly lock the parts in position. 75

It is furthermore an important object of this invention to construct an improved frame for school desks and seats to receive a desk and seat mounted thereon, each independently adjustable and capable of being rigidly secured in any adjusted position, preventing accidental or unauthorized adjustment of the parts. 80

It is finally an object of this invention to improve the general construction of school 85 desks and seats, facilitating the assembly thereof and affording an element of adjustability to suit the convenience of persons of different stature, which is simple in design and construction and capable of adjustment by an inexperienced person. 90

The invention (in a preferred form) is illustrated in the drawings and hereinafter more fully described.

In the drawings: Figure 1 is a side elevation of a device embodying the principles of my invention with the operation illustrated in dotted lines. Fig. 2 is a front elevation thereof. Fig. 3 is a section taken on line 3—3 of Fig. 2. Fig. 4 is a fragmentary detached rear elevational view of the adjustable desk member. Fig. 5 is a section taken on line 5—5 of Fig. 1, but with the seat back shown in elevation. Fig. 6 is a fragmentary enlarged view illustrating a 95 part of the frame. Fig. 7 is a detail section taken on line 7—7 of Fig. 1, with parts shown in elevation. Fig. 8 is an interior face view of the clutch or locking member. Fig. 9 is a detail section taken on line 9—9 100 of Fig. 7. Fig. 10 is a detail end view of a seat hinge member. Fig. 11 is a detail sec-

tion taken on line 11—11 of Fig. 9. Fig. 12 is a detail section taken on line 12—12 of Fig. 4, with parts omitted.

As shown in the drawings: The reference numeral 1, indicates as a whole one of two rigid base frames provided with feet permitting the same to be screwed to the floor, each of said frames being exactly similar in construction with the exception that one is a right side and the other a left side frame member. Formed integral with said frame member 1, is an extension 2, which on its interior surface, is provided with vertical ribs 3, cast integral therewith and affording a guideway therebetween. A notch or corrugated slot 4, is disposed vertically, though not necessarily so, in each of said frame extensions 2, between the ribs 3, and slidably mounted upon the interior face of each of said frame extensions 2, in the guideways thereof are hinge members 5 and 6, respectively, each having an integral gudgeon pin projecting from the surface thereof through the respective slots 4, the gudgeon pin on the member 5, being denoted by the reference numeral 7, and slightly longer than the gudgeon pin denoted by the reference numeral 8, on the member 6, as clearly shown in Fig. 7. Said members 5 and 6, are each provided with integral side flanges 9, which overlap the guide ribs 3, although as clearly shown in Fig. 7, when the hinge members are in an adjusted position in the frame extension 2, the hinge member 6, does not lie closely against the frame, being supported, however, therein in the notched slot 4, by means of its gudgeon pin 8.

Formed integrally on the upper end of each of the respective members 5 and 6, are rounded pivot heads 10, which fit rotatably into integral hinge members 11, cast therearound. This construction is obtained in a novel manner, the hinge member 5 or 6, as the case may be, being made first. The head 10, thereon, is then dipped into molasses and then into parting sand, and a segmental core is then attached on the periphery thereof, and the whole used as a core for a mold in which the hinge member 11, is formed. The core attached on the head 10, forms the peripheral slot 12, which is clearly shown in Fig. 11, in the hinge member 11, the attached core having been of such a length and in such a position as to form a slot 12, in the hinge member 11, with the integral projection 13, on the head 10, disposed in the slot so formed. The projection 13, moving in said peripheral slot 12, thus acts as a means for limiting the rotational movement or throw between the respective connected hinge members. As clearly shown in Fig. 10, the hinge member 11, is extended in length and curved and provided with a dovetail tongue 14, thus permitting the slats, composing a seat 15, to be engaged thereon.

At the rear end of the tongue 14, on each of the hinge members 11, an integral lug of metal 16, is formed, which acts as a stop for the slats comprising the seat 15, when the same are engaged upon the hinged members, so that it is only necessary to secure the outermost slat of the assembled seat in position. This is done by a single screw 17, which may be engaged through an aperture in the hinge member 11, which is attached to the hinge member 5, and threaded into the under surface of the outermost slat of the seat.

As clearly shown in Fig. 7, the respective gudgeon pins 7 and 8, of the hinge members are each provided with a narrowed cut-away or recessed surface, in each case denoted by the reference numeral 18, so that when said hinged members 5 and 6, are shifted to the right from the position shown in Fig. 7, the recessed portions of said gudgeon pins will be registered between the notches in the respective slots 4. The gudgeon pins are thus permitted to move longitudinally in the slots for adjustment desired, and after which of course the hinge members 5 and 6, are shifted again to the left, so that the rounded portions of said pins engage in the round notches of the slots, and are prevented from movement. In order to prevent an accidental or unauthorized shifting movement of said hinge members 5 and 6, from the position shown in Figs. 2 and 7, a clutch or locking member is provided for engagement upon the gudgeon pin 7. This member consists of a single integral block 19, which is cored out on its interior to afford a recess 20, therein, and on one of its surfaces is provided with a key-hole-shaped slot 21, as clearly shown in Fig. 8. The circular portion of said slot 21, is sufficiently large to permit the block to be inserted over the rounded outer end of the gudgeon pin 7, and then permitting said block to be moved downwardly with the convergent edges of the key-hole slot wedging on each side of the recessed portion 18, of the pin. This prevents retraction of the pin through the slot 4, of the frame extension 2, and consequently prevents unauthorized adjustment of the hinge members. It will be apparent therefore that the narrowed flat portion 18, of the gudgeon pin 7, serves two purposes, that of permitting an adjusting movement of the pin in the slot 4, and also as a means of engagement for the locking member 19, upon the pin.

Although the locking member 19, acts efficiently and positively upon the gudgeon pin 7, to hold the hinge members shifted, as shown in Fig. 7, still it is possible, especially in a schoolroom, that a mischievous child might kick the same upwardly, thus detaching the same. In order to prevent this occurrence a tapered pin 22, may be

driven through apertures provided in the lower end of said block 19, so that the pin is disposed beneath the head of the gudgeon pin 7, thus preventing said block being 5 thrust upwardly out of engagement with the gudgeon pin, except when said tapered pin is first removed.

Mounted on the upper front edge of said frames 1, are a series of wooden slats 23, being engaged upon dovetail tongues similar to those described, to afford a back for said seat 15, and with the uppermost of said slats 10 of the back 23, secured in position by a screw to hold all of the slats properly engaged upon the frame members.

The desk top is designated by the reference numeral 24, and is provided with a dovetail groove, to permit engagement thereof upon side bracket frames 25 and 26, respectively which, on their inner surfaces, are each provided with ribs 27, to permit the insertion of a shelf board or member 28, therein. Said respective desk and shelf members are held in secured position by a single 25 screw, denoted respectively by the reference numerals 29 and 30, in Fig. 3.

Formed integrally on the exterior surface of the bracket frame 26, are gudgeon pins 31, each having a flat narrowed recessed portion 32, corresponding to the recessed portions 18, of the pins 7 and 8, before referred to. Similarly formed on the exterior surface of the bracket frame 25, are recessed gudgeon pins 33 and 34, the pin 34, being 35 longer than either the gudgeon pins 31 or 33. A number of notched or corrugated slots for the reception of said respective gudgeon pins 31, 33, and 34, are provided in the frame members 1, and are denoted by 40 the reference numerals 35 and 36, respectively. The adjustable desk top and bracket frames rigidly associated therewith are held in an adjusted position by a locking member designated by the reference numeral 37, 45 which is exactly similar in construction to the locking member 19, before described, and when in use is attached upon the long gudgeon pin 34, of the desk top frame member 25. A kick board 38, is mounted between 50 the respective frame members 1, as clearly shown in Figs. 2 and 3.

The operation is as follows: The hinge members which support the seat 15, move in guides provided on the main frame 1, and 55 are adjustable vertically therein, but only after the seat member as a whole has been shifted transversely of the frame in order to bring the gudgeon pins 7 and 8, respectively into a position such that the recessed 60 or flat narrowed portions of said pins are registered in the slots 4, of the frame, so that an adjusting movement of said pins in the slots is permitted. After the seat has been 65 adjusted, of course it is again shifted transversely, so that the rounded portions of the

pins engage in the rounded recesses or notches of the slots, and the hinge members are thus rigidly supported in position. The purpose of the lock or clutch member 19, is to prevent a transverse displacement of the 70 seat accidentally after the same has been placed in an adjusted position, the entire weight, however, being borne by the gudgeon pins, the guides or ribs 3, on each of the hinge members serving to give the construction 75 rigidity.

In order to attach the locking block 19, it is only necessary to insert the enlarged rounded end of the keyhole slot 21, over the rounded end of the pin 7, and then slide the 80 member downwardly with the edges of the slot 21, engaging in the recessed portion 18, of the pin, so that the outer rounded end of said pin is engaged in the recess 20, within the block beneath the convergent edges of 85 the slot 21. As a further precaution against an unauthorized adjustment of the seat, said locking member 19, is provided with a cotter pin 22, which is driven through apertures provided therein for the purpose, and 90 is disposed beneath the end of the pin 7, so that said block cannot be detached unless said pin 22, is first removed.

As already pointed out in the specification, the hinges for the seat are of novel 95 construction, being inseparably connected with one another. That is to say, the hinge members 11, are actually molded around the pintle heads 10, of the hinge members 5 and 6, and the projection 13, on said pintle heads 100 limits the movement of the hinge members 11, according to the length of the peripheral slot 12, formed therein, as clearly shown in Fig. 11. The two positions of movement of the seat limited by said projection 13, are clearly shown in Figs. 1 and 3. In providing for the adjustment of the desk top of the device, an identical construction is involved. However, two sets of slots, each denoted by the reference numerals 35 105 and 36, are provided in the frame members 1, so that four slots are used to support the desk top and the shelf member 28, which is associated therewith. The side bracket frames 25 and 26, are adjustable in the main 110 frame members 1, being provided with gudgeon pins engaging in the aforesaid slots 35 and 36, and one of said gudgeon pins, that is, the pin 34, being longer than the rest, similarly to the pin 7, before described, in 115 order to permit engagement thereon of a lock or clutch member 37. The seat and desk are designed so that the middle adjustment of the pins in the respective slots is used for a child of normal stature, and then 120 the respective parts may be lowered or raised accordingly, to accommodate a smaller or larger child, as the case may be. The length of the slots is immaterial, and may be varied to suit conditions, of course the 125 130

greater the length of the slots the greater the amplitude of adjustment of the parts. If desired, of course the back 23, of the device may be rigidly associated with the desk 5 top 24, and made adjustable therewith, or if desired may be made independently adjustable by another series of gudgeon pins and slots, it being obvious in view of the construction disclosed that such a modification 10 would fall well within the scope of my invention.

I am aware that various details of construction may be varied through a wide range without departing from the principles 15 of this invention, and I therefore do not purpose limiting the patent granted otherwise than necessitated by the prior art.

I claim as my invention:

1. The combination with frame members 20 having slots therein, said slots having notched edges, of means adjustably mounted on said frame members, gudgeon pin extensions on said means projecting through said slots, said pins having recesses therein adapted when said recesses are shifted into register with the edges of said slots to permit adjusting movements of said means and when shifted out of register with said slots preventing adjusting movements of 30 said means, and wedge clutch mechanisms adapted to interlock with the recesses of certain of said pins to prevent shifting movements thereof for adjustment of said means.
2. In a device of the class described, frame members having slots therein, hinge members adjustably mounted on said frame members, gudgeon pins integral with said hinge members projecting through the slots in 40 said frame members, said pins having recesses therein adapted when said hinge members are laterally shifted whereby said recesses are in register with the edges of said slots to permit adjustment of said hinge members in said frame members and when adjusted out of register with said slots preventing adjustment of said hinge members, and clutch blocks adapted to be engaged on the outer end of certain of said gudgeon pins 45 interlocking with the recesses thereof to lock the same and preventing shifting movement of said hinge members and gudgeon pins in the frame members.
3. In a device of the class described, frame 55 members, hinge members adjustable thereon, gudgeon pins extending through slots in said frame members and rigid on said hinge members, and wedge clutch blocks adapted to wedgingly engage on the outer end of certain of said gudgeon pins preventing shifting movement thereof to lock 60 said hinge members on the frame members.
4. In a device of the class described, frame members, hinge members adjustably

mounted thereon, gudgeon pins integral on 65 said hinge members and projecting through slots provided therefor in said frame members, and a cored out locking block adapted to engage over the outer end of certain of said gudgeon pins and preventing shifting 70 movement thereof with the hinge members to lock the hinge members in adjusted position with respect to said frame members.

5. In a device of the class described frame members having slots therein with notches 75 in the sides thereof, hinge members mounted on said frame members, gudgeon pins on said hinge members engaging in said slots and having recesses therein to permit movement thereof in said slots, a seat mounted 80 on said hinge members, and mechanism to lock said hinge members from adjustment in said slots by engagement with the recesses in the hinge gudgeon pins.

6. In a device of the class described a 85 frame, hinges vertically adjustable and laterally shiftable therein, gudgeons integral with said hinges projecting through slots in the frame, a seat mounted on said hinges, and mechanism adapted to be detachably engaged on one of said gudgeons to lock said 90 hinges from lateral shifting movement to hold the hinges from vertical adjustment in said frame.

7. In a device of the class described, frame 95 members, hinge members adjustable thereon, integral gudgeon pin extensions on said hinge members projecting through slots in said frame members, said slots having notched edges adapted to receive the pins in 100 one position to lock the same from adjustment therein and thereby support said hinge members rigidly in the frame members and permitting adjusting movements of said hinge members when the hinge members are 105 shifted laterally in the frame members, and a wedge block adapted to be detachably engaged over the outer end of one of said gudgeon pins to lock said hinge members from lateral movement in the frame members. 110

8. In a device of the class described a frame, guides formed thereon, hinge members mounted to move in said guides, slots in said frame, means on said hinge members 115 engaging in said slots and having recesses therein permitting movement of said hinge members when said recesses are shifted into register with said slots, and mechanism adapted to engage said means interlocking 120 with said recesses therein to prevent adjustment of said hinge members in the frame.

9. In a device of the class described a frame, guides formed thereon, hinge members mounted on said frame and movable in said guides, a seat connected on said hinge members, said hinge members 125

capable of a lateral shifting movement preliminary to movement in said guides, and a clutch wedge mechanism attachable on one of said hinged members to prevent said shifting movement and adapted to be detached therefrom to permit shifting and adjusting movements of said hinges and seat connected thereon.

10. In a device of the class described a frame having slots therein, the edges of said slots notched, a plurality of members mounted for adjustment on said frame, means on said members engaging through said slots, one of said means longer than the other 15 thereof and all of said means in one position rigidly locked from movement, and when shifted laterally capable of adjustment, and mechanism attachable on the outer end of said longer means to prevent said shifting movement and lock said members from adjustment in the frame.

11. In a device of the class described a frame, seat and desk members adjustable therein, means for locking the same in an 25 adjusted position comprising cored out blocks each having a keyhole slot in the surface thereof, and a pin on said seat and desk members each one adapted to receive a block engaged thereon.

30. 12. In a device of the class described a frame having slots therein, the edges of said slots notched, hinged members adjustably mounted on said frame, projecting pins thereon adapted to engage through said 35 slots, and recessed to permit movement from one notch to another in said slots after being shifted laterally therethrough, and a locking member adapted to be engaged on a pin to prevent shifting movement thereof 40 comprising a cored out block having a key-hole slot in the surface thereof for engage-

ment over said pin and attachment on the outer end thereof.

13. In a device of the class described a frame having slots therein, the edges of said 45 slots having a plurality of notches therein, hinge members adjustably mounted in said frame, pins thereon engaging in said slots and having recesses therein, said pins when in position with their recesses out of register 50 with said slots prevented from movement therewith and when shifted laterally therethrough with their recesses registered therewith capable of adjustment in said slots, and means adapted to be engaged on said 55 pins interfitting with the recesses therein to prevent lateral shifting thereof and consequent adjustment in said slots.

14. In a device of the class described a frame, slots therein having notches in the 60 edges thereof, members adjustable on said frame, pins thereon engaging through said slots, said pins having recessed portions which when shifted into register with the edges of said slots, permit movement of the 65 pins along said slots and said members therewith, and when shifted out of register with said slots, prevent movement of said pins and members along said slots, and means attachable on the ends of said pins 70 interlocking with the recessed portions adapted when attached thereon to prevent shifting movement thereof to lock said members in an adjusted position on said frame.

In testimony whereof I have hereunto subscribed my name in the presence of two subscribing witnesses.

HENRY E. MAXWELL.
